LIGHTING DEVICE FOR JACK-O'-LANTERNS
AND OTHER HALLOWEEN TOYS

Howard S. Root, Spokane, Wash.

Application December 21, 1948, Serial No. 66,408

2 Claims. (Cl. 240—16)

1

My present invention relates to improvements in a lighting device for jack-o'-lanterns and other halloween toys.

It is the principal purpose of my invention to provide a novel construction of lighting device for jack-o'-lanterns and other Halloween toys. These toys generally of jack-o'-lantern pumpkin form, but sometimes in imitation of animals or human heads, are commonly used by children at Halloween time. Their attractiveness is greatly enhanced by illumination from within. Various means for lighting them have been employed. The most common device is an ordinary candle. That, however, is very dangerous. The toys are often made of fibrous material and colored with lacquer. The combination is often highly inflammable. Moreover the candle itself may ignite a child's clothing.

According to my invention, it is the purpose to provide a lighting means for such toys using an ordinary dry cell battery which embodies a battery container having means to attach it to the toy on the interior and having hinged thereto a combination light bulb support and switch mechanism operable by a handle that protrudes from the toy at a distance from the bulb and battery. In the preferred form of the invention, the handle also cooperates with the hollow shell to produce noise.

The objects and advantages of my invention will appear more fully from the following description and the accompanying drawings illustrating a preferred embodiment, with modifications of certain parts thereof, of the invention. The drawings and description, however, are illustrative only and it will be apparent that many changes in the detailed construction may be made within the scope of my invention.

In the drawings:

Figure 1 is a vertical sectional view through a hollow toy embodying my invention;

Figure 2 is a fragmentary side view of a part of the battery and light holding device;

Figure 3 is a fragmentary side view taken on the line 3—3 of Figure 1;

Figure 4 is a fragmentary side view taken on the line 4—4 of Figure 1;

Figure 5 is a plan view of the battery and light holding device;

Figure 5a is a bottom view of the battery and light holding device;

Figure 6 is a sectional view similar to Figure 1, showing a modified handle and mounting for the light bulb, this device being operable from the side;

2

Figure 7 is a plan view of the lighting device of Figure 6;

Figure 8 is a plan view of a further modified construction of the lighting device;

Figure 9 is a sectional view on the line 9—9 of Figure 8;

Figure 10 is a sectional view similar to Figure 1 of a further modification of the device;

Figure 11 is a sectional view on the line 11—11 of Figure 10.

Figure 12 is a side view of the lighting device of Figure 10, looking at it from the right hand side of Figure 10; and

Figure 13 is a sectional view on the line 13—13 of Figure 10.

Referring now to Figures 1 to 5a inclusive showing the preferred form of my invention, I provide a container in the form of a substantially U-shaped bracket 10, of any suitable material, to provide a seat for a battery 11 and to provide the mounting means for a light bulb 12 and operating mechanism, described more fully later, by which the light bulb 12 may be energized from the battery 11. The bracket is electrically conductive to provide a conductor for completing the circuit to the light bulb 12.

The container 10 has depending fingers 13 and 14 oppositely disposed at the bottom thereof. These fingers preferably are struck up from the material at the side of the container as shown in Figure 5. The fingers are forced through the base of the hollow toy 9 (jack-o'-lantern, black cat etc.), and clinched over a metal washer 8 that seats in a shallow ring like recess 9a that is formed in the bottom of the toy 9. This construction reinforces the connection of the container 10 to the bottom of the toy and keeps the fingers from pulling out. The fingers may also be struck out of the bottom of the container as shown in Figure 5a.

In order to resist removal of the battery, it is preferred to make the container 10 of somewhat resilient material so that it will grip the battery. The upstanding legs 10a and 10b are curved transversely to prevent the battery from sliding out sideways. The tongues 15 are struck out from the material of the bracket legs 10a and 10b to serve further to secure the battery 11 against dislodgement. A band 16 is also used to keep the legs 10a and 10b in place.

At the top of one leg 10a, I provide a hinge 17 for a light bulb support 18. This support is provided with an aperture 19 which is threaded to receive the light bulb 12. By swinging the support 18 up and down, the light bulb 12 is brought into contact with the flat end terminal

11a of the battery 11 to complete the energizing circuit for the light bulb 12. The other contact for the battery is between the raised center terminal 11b on the battery and the cross bar 10c forming the bottom of the bracket 10.

In a device of this character which is to be carried by children, it is essential to simplify the construction for energizing the light bulb, but to make it of such nature to withstand the rough handling of children at play. I provide an operating means for the light bulb support 18 of such a nature that the child can turn the light on and off at will, yet if the entire toy is carried by the operating handle, no harm is done to the device. As illustrated in the several drawings, this operating mechanism may be varied considerably in detail but in all instances it is characterized by a handle 20 extending through an aperture in the hollow toy, either at the top or the side of the toy, and freely movable in the aperture to move the bulb support 18. In the preferred form (Figures 1 to 5) the handle 20 goes through the top opening 23 in the jack-o'-lantern and rocks to and fro in this opening. By shaking the jack-o'-lantern to and fro, the handle 20 can be made to strike the walls of the jack-o'-lantern and make a drumming noise while it also flashes the light bulb.

The support 18 and the container 10 carry co-operating parts acting yieldingly to hold the support 18 in light bulb energizing position when it is moved there by the handle 20. The leg 10a is provided with ears 21 and the support 18 has a hinge pin 22 thereon cooperating with the ears 21 to form the hinge 17. A spring 25 has one end hooked over a shoulder 24 formed by bending over the upper end of the leg 10a. The spring 25 is wound on the pin 22 and hooked over the support 18 to oppose movement of the support 18 to an open position from the closed circuit position shown. The handle 20 has its lower end pivoted in a bent over portion 26 of the leg 10b and has an operating portion 27 for engaging and lifting the support 18. Even if the child carries the toy by the handle 20 and swings it around or bangs it against something, the strain is direct from the handle to the leg 10b, thus protecting the light bulb 12 and its support 18 from damage.

In Figures 8 and 9 the hinge construction at 17' is somewhat different. The support 18' has an aperture 18a therein and the leg 10a has a portion 28 extended through the aperture 18a and curled over. This is a loose hinge construction. Extended prongs 29 on the support 18' cooperate with spring lugs 30 on the leg 10a' to oppose movement of the support 18' to bring the bulb 12 against the central terminal of the battery 11. In this form of the invention the support 18' is held in closed position by a permanent magnet 31 that is secured on the leg 10b' of the battery container. The support 18' must of course, be at least in part, of a material that will be attracted by the magnet 31. Soft iron or steel which is also a conductor of electricity may be used. The loose hinge construction allows the spring lugs 30 to force the support 18' down to take care of slight differences in battery heights. The handle 20 is connected to the free end of the support 18'.

In Figures 6 and 7 of the drawings the hollow toy 9' has a side opening 32 in addition to the usual top opening 23. In this form a lamp support 33 of wire is hinged at 17 to the container 10. The wire support 33 is coiled at 34 to receive the lamp 12 and is extended by a sliding exten-

sion 35 through the opening 32. Pressure on the handle extension 35 can be replaced, the handle extension 35 can be extended 36 will force the lamp 12 down to contact the battery 11. When the battery 11 is to be replaced, the handle extension 35 can be pushed in and lifted through the opening 23. The lamp 12 is normally held out of contact with the battery 11 by a resilient member 36 of rubber or its equivalent.

10 In Figures 10, 12 and 13, the construction for mounting the lamp support 18" is modified. In this form of the invention two ears 37 are extended from the leg 10a of the U-shaped battery container. The ears 37 are bent around laterally extending projections 38 that are formed on the support 18". A resilient tongue 39 of the leg 10a is curved and extended as shown in Figure 10, to provide a spring latch engaging an extension 40 of the support 18". The contour of 20 the tongue 39 is such that it permits the support 18" to snap between open position, where the lamp 12 is spaced from the battery 11, and closed position, where the lamp 12 is brought into contact with the battery 11.

25 The manner of holding the band 16 in place is somewhat different in Figure 10 from the showing in Figure 1. It is obvious, however, that this and other minor changes may be made within the scope of my invention. The function of the band 16 is merely to hold the legs of the container 10 more securely and it may be dispensed with where the container is sufficiently rigid.

30 As shown by the drawings and the foregoing description, I have provided a safe lighting device for jack-o'-lanterns and other toys. It is my desire to utilize this lighting device in such toys that are adaptable to it or which are designed for it. The preferred form also is a noise maker to increase the appeal of these toys to children. When the battery is used up, it can easily be replaced by lifting the support 18 and then lifting the battery. The preferred form is also a light weight, inexpensive, easily manufactured device, capable of forming, by simple and easy engagement with an electric bulb and dry cell battery, a safe light for such toys.

35 From the foregoing description it is believed that the nature and advantages of my invention will be clear.

Having thus described my invention, I claim:

1. An illuminated figure toy comprising a hollow body having an opening in the top thereof and having side openings for lateral passage of light from the interior of the body, a container for a dry cell battery secured in the body and having oppositely disposed portions projecting above the level of a dry cell battery seated in said container, a dry cell battery seated in said container, the battery having a central terminal at its bottom and engaging the container, the container being electrically conductive, a lamp bulb, an electrically conductive support hinged to one of said portions and extending over the other portion, said support having a socket in which the lamp bulb is mounted, the lamp bulb having an end terminal directed toward the adjacent end of the battery, spring means on the container urging the support in a direction to press the end terminal of the lamp bulb against the end of the battery to establish electrical contact between the lamp bulb and the battery, a handle operably connected to the support and extending to the exterior of the body through one of the openings for moving the support against the pressure of said spring means thereby to

separate the end terminal of the lamp bulb from the battery.

2. An illuminated figure toy comprising a hollow body having an opening in the top thereof and having side openings for lateral passage of light from the interior of the body, a container for a dry cell battery secured in the body and having oppositely disposed portions projecting above the level of a dry cell battery seated in 10 said container, a dry cell battery seated in said container, the battery having a central terminal at its bottom and engaging the container, the container being electrically conductive, a lamp bulb, an electrically conductive support hinged to one of said portions and extending over the 15 other portion, said support having a socket in which the lamp bulb is mounted, the lamp bulb having an end terminal directed toward the adjacent end of the battery, spring means on the container urging the support in a direction to 20 press the end terminal of the lamp bulb against the end of the battery to establish electrical contact between the lamp bulb and the battery, a handle pivoted on said other projecting portion and extending through the top opening of 25 the hollow body, said handle being swingable

about its pivot from side to side of said opening to act as a beater on the hollow body to produce noise, said handle having a portion extending beneath the free end of said support and engaging the said support and lifting the support against the force of said spring means when the handle is moved in one direction into engagement with the side of the top opening of the hollow body.
